UNITED STATES PATENT OFFICE.

JOSEPH LANGUIRAND, OF WOONSOCKET, RHODE ISLAND.

PICKER-STAFF FOR LOOMS.

SPECIFICATION forming part of Letters Patent No. 515,344, dated February 27, 1894.

Application filed October 24, 1893. Serial No. 488,997. (No model.)

To all whom it may concern:

Be it known that I, JOSEPH LANGUIRAND, a citizen of the United States, residing at Woonsocket, in the county of Providence and 5 State of Rhode Island, have invented certain new and useful Improvements in Picker-Staffs for Looms; and I do declare the following to be a full, clear, and exact description of the invention, such as will enable others skilled 10 in the art to which it appertains to make and use the same.

My invention relates to improvements in picker staffs for looms and more particularly to means for effecting a connection between 15 the picker staff and the connecting bar or stick for transmitting motion to said staff; and it has for its general object to provide a simple and durable device through the medium of which the tug of the connecting bar 20 or stick may be adjustably fixed at various points on the picker staff so as to regulate the throw of said staff and that of the shuttle without the objectionable necessity of perforating the staff or otherwise weakening the 25 same.

Other objects and advantages will be fully understood from the following description and claims when taken in connection with the annexed drawings, in which—

30 Figure 1, is a perspective view of so much of the mechanism of a loom as is necessary to illustrate my invention. Fig. 2, is a detail view of the picker staff with my improved device in position thereon; a portion of said device together with the tug of the connecting 35 bar being illustrated in section, and Fig. 3, is an enlarged detail section taken in the plane indicated by the line $x-x$, of Fig. 2.

Referring by letter to said drawings: A, indicates the lay of a loom; B, indicates the picker staff; C, indicates the arm of the rocker shaft (not illustrated); D, indicates the connecting bar or stick, and E, indicates the staff-receiving tug carried by the bar or stick D, 45 all of which may be of the ordinary or any approved construction.

The rocker-shaft arm C, and the picker staff B, are connected as better shown in Fig. 2, by a bolt F, and this bolt also serves to effect a 50 connection between the picker staff and my

improved adjusting device G, the body portion a , of which is mounted on the bolt between the arm C, and the picker staff, as shown.

The body portion a , of the device G, is preferably formed from malleable iron or other 55 suitable metal and it is provided with an apertured post c , and a guide lug d , to receive the shank e , of the adjustable section H, and is also provided at intervals with transverse sockets f , to receive the angular stud g , of the 60 said shank.

As better shown in Fig. 1, the loop or eye I, of the section H, receives the tug E, of the bar or stick D, and it is provided at its ends with the transversely disposed curved portions h , which present a convex surface to the loop E, and thereby prevent unnecessary frictional wear of the same. The shank e , of the adjustable section extends as before stated, through the apertures of the lug d , and post 70 c , and its stud g , is designed to be fixed in any one of the apertures f , by the binding screw i , which takes through the post c , and engages the shank as shown. By this construction it will be seen that the loop or eye 75 I, may be readily and positively fixed at various distances from the free end of the picker staff to increase or diminish the throw of the said staff, without the objectionable necessity of perforating or otherwise weakening the 80 same. It will also be seen that my improved device has no direct connection with the picker staff and consequently when said staff is worn or broken, it may be readily removed and a new staff employed in conjunction with the 85 adjusting device.

From the foregoing description and the drawings, it will be noted that my improved device is very simple, durable and easily operated, and it will also be noted that it may 90 be applied to looms such as at present in use without changing any of the parts of the same and without the employment of skilled labor which is a desideratum. It will also be noted that the adjusting device braces and prolongs 95 the usefulness of the picker staff since it receives a portion of the strain placed thereon.

Having described my invention, what I claim is—

1. The combination with a picker staff, and 100

a connecting bar or stick carrying a tug to receive the picker staff; of an adjusting device comprising a body portion having a series of sockets at intervals in its length, an adjustable section adapted to engage the tug of the connecting bar or stick and having an angular stud adapted to engage the sockets of the body portion and a suitable means for removably fixing the angular stud of the adjustable section in any one of the sockets of the body portion, substantially as and for the purpose set forth.

2. The combination with a picker staff and a connecting bar or stick carrying a tug to receive the picker staff; of an adjusting device comprising a body portion having a series of sockets at intervals in its length and also having an apertured lug and an apertured post and a binding screw mounted in said post, and an adjustable section adapted to engage the tug of the connecting bar or stick and having an angular stud adapted to engage the sockets of the body portion, substantially as specified.

3. The combination with a picker staff, its pivot, and a connecting bar or stick carrying a tug to receive the picker staff; of the ad-

justing device comprising the body portion or plate mounted on the pivot of the picker staff and having sockets at intervals in its length 30 and also having a guide lug and a post carrying a binding screw, and an adjustable section having a loop or eye adapted to receive the tug of the connecting bar or stick, and a shank having an angular stud to engage the 35 sockets of the body portion, substantially as specified.

4. As an improved article of manufacture, the adjusting device herein described, comprising the body portion having a series of 40 sockets at intervals in its length, and also having the guide lug *d*, and the post *c*, carrying a binding screw, and the adjustable section having a loop or eye and a shank adapted to take through the guide lug and post of the 45 body portion and provided with an angular stud adapted to engage the sockets of said body portion, substantially as specified.

In testimony whereof I affix my signature in presence of two witnesses.

JOSEPH LANGUIRAND.
